UNITED STATES PATENT OFFICE.

CHARLES S. HALL, OF LOS ANGELES, CALIFORNIA.

AIRCRAFT.

Application filed April 26, 1920. Serial No. 376,846.

To all whom it may concern:

Be it known that I, CHARLES S. HALL, a citizen of the United States, residing in Los Angeles, county of Los Angeles, and State 5 of California, have invented certain new and useful Improvements in Aircraft; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 This invention relates, generally, to improvements in aircraft; and, the present invention has reference more particularly to an aeroplane provided with a vertical lifting propeller over a body of vertical stream- 20 line, and a means of operating said lifting propeller by engine power, thus enabling the pilot to control the same whereby the aircraft may be raised from the ground without, or with a reduced amount of, forward 25 motion along the ground and to enable the pilot to allow the return of the aeroplane to the ground gradually and without, or with a reduced amount of, forward motion along the ground.

30 A further object being to provide an opening within the planes over, or near, the center of gravity of the whole aircraft, said opening to be around the lifting propeller and the said planes to be provided with slid- 35 able members which may be moved along both the upper and lower surfaces of the said planes whereby the said opening around the lifting propeller may be closed so as to enclose said propeller within the planes 40 when the said propeller is not in use, thus utilizing, in forward motion, the surface area of the said opening.

A further object of the invention being to provide a means of opening and closing 45 portions of the lower planes by slidably moving members or sliding wings, whereby the air currents from the lifting propeller above may be permitted to pass downwards and around the fuselage.

50 The present invention is an improvement

upon those disclosed in patent numbered 1,307,826, dated June 24, 1919 and patent application filed under Serial Number 328,558.

Other objects of this invention not at this 55 time more particularly enumerated will be clearly understood from the following detailed description of this invention, and clearly illustrated in the accompanying 60 drawings, in which:—

Figure 1 is a top view taken from a for- 65 ward position showing both the upper and lower left wings and the lower right wing, showing the sliding wings moved in outward position and disclosing openings provided in 70 the planes.

Figure 2 is a perspective view of the sliding wing removed from the plane with the supporting rods passing through the sliding 75 sleeves of said wings.

Figure 3 is a fragmentary view of plane 80 spar showing the sliding sleeve and the supporting rod attached to said spar.

Figure 4. is a fragmentary perspective of 85 a part of sliding wing showing a cross sec- 75 tion of telescoping interlocking rib.

Figure 5. is a top view of plane with both 80 sliding wings partly closed and showing a part of the opening in the plane showing a part of the cable strands by the use of which 85 the said sliding wings are operated, the other part of the control is not here shown.

Figure 6, is the same view as Figure 5 except in this view the sliding wings are 90 completely closed over and around the lift- 85 ing propeller opening.

Figure 7. is a longitudinal side view of 90 the fuselage, all attachments and planes re- 95 moved, showing the streamline for horizontal motion through the air.

Figure 8. is a cross section of the fuselage at the points where the lifting propeller is placed, showing the streamline of said fuselage.

Figure 9. is a perspective view of essential 95 portions of assembled aircraft showing all features of this invention in operative relation, with sliding wings in outward position, with propeller showing in the lifting posi- 100 tion in the upper plane and the openings in

the lower plane providing for the downward passage of the slip-stream from the lifting propeller.

In carrying out my invention a fuselage 5 1 is provided. This fuselage is streamlined horizontally as shown in Figure 7, and vertically, as shown in cross section in Figure 8. In this fuselage a lifting propeller 2 is placed over or relatively near the center of 10 gravity of the aircraft. Supporting planes 3 and 4 are attached to said fuselage, and said planes provided with openings 5 and 6. Within opening 5 of the upper plane a rotatably mounted lifting propeller is placed, as 15 shown in Figure 9. On plane 3 are placed two slidably disposed wing sections 7 and 8, and on plane 4 are also placed two slidably disposed wing sections 9 and 10, and shown in Figures 5, 6, and 9, showing said wing 20 sections in various positions. These wing sections are composed of two members 7^A, and 7^B, as shown in Figure 2 and in Figure 9, and held in telescoping, overlapping and sliding relation by three interlocking 25 ribs 11, as shown in Figures 1 and 2, one of which is shown in cross section in Figure 4. The interlocking rib, as shown in Figure 4, is composed of two members 12^A and 12^B as shown in Figure 4. Each portion of sliding 30 wing section is fastened to a sleeve 13 by any suitable means, as shown in Figures 2, 3, and 9. Rod 14, as shown in Figures 1, 2, 3, and 9 is fastened to the spar of the plane by any suitable fastenings as shown in Figure 35 3. To each portion of the sliding wing is fastened suitable pulleys 15 as shown in Figures 1, 5, 6, and 9, to which cable strands 16 shown in Figures 1, 5, 6, and 9 are run through from suitable fastenings on wing 40 portions to the lever control 17 in pilot box 18.

All of the frame work of fuselage, planes, and sliding wing surfaces are covered with suitable cloth or other material.

45 Having in the foregoing description given general details of arrangement and combination of parts composing the essential principles of this invention, I will now briefly describe its operation.

50 When pilot by manipulation of lever 17 connected with cable strands 16 operating through pulleys 15 moves outwardly the sliding wings 7, 8, 9, and 10, these wing portions adjust their length along rod 14 by 55 means of sleeve 13, and also by means of the interlocking telescoping ribs, thus propeller 2 is exposed to the air. Then by starting the motor, by suitable control, said propeller is set in rotation and the resultant downward 60 rush of the air follows the contour of the vertically streamlined fuselage 1, with the result that the aircraft is raised from the ground. After sufficient height is reached

the horizontal propeller is set in motion and the sliding wing members are moved inwardly until the opening around the propeller 2 and the said propeller is stopped, thus the planes are completely closed and the propeller is enclosed within the upper plane of the aircraft. Then in making landing, after the horizontal propeller is stopped while in the air the pilot through the aforesaid control moves outwardly the sliding wings and thus exposing the openings in the planes and exposing the vertical lifting propeller 2, said propeller is set in motion and the aircraft is gradually permitted to settle down to the ground.

I am aware that various changes in arrangements and combinations of parts, as well as in the details, can be made without departing from the spirit of this invention and I do not wish to confine myself to the biplane or the multiplane type of aircraft as it is understood that this invention may be used upon the monoplane type also.

I claim:

1. In an aircraft of a heavier-than-air type the combination, a vertically streamlined fuselage, a lifting propeller rotatively mounted near the center of gravity of the said aircraft, an opening provided in the planes adjacent to said propeller, a means of permitting the downwardly induced air-stream to pass through the openings in the said planes and around the fuselage, interlocking ribs to be used on sliding wing portions, and a means of extending and withdrawing the said sliding wings whereby the openings provided in the said planes may be closed.

2. In an aircraft having a vertically stream-lined body, the combination of a lifting propeller rotatably mounted and operatively arranged adjacent to the center of gravity, and a means of opening and closing wing surfaces above and below the said propeller so that the air-stream downwardly induced by the propeller in operation will be permitted to pass down and around the fuselage of the said aircraft.

3. In an aircraft having a vertically stream-lined body, the combination of a lifting propeller operatively mounted, adjacent to the center of gravity of the said aircraft, and so arranged that, by the rotation thereof, the air-stream induced from the said propeller will be disposed transversely to the normal line of flight of the said aircraft, sliding wing portions operatively arranged whereby they may be moved outwardly and inwardly so as to open and close an opening provided in the planes adjacent to the said propellers, an interlocking rib so arranged that the exposed area of the sliding wings may be varied as the same are moved out-

wardly and inwardly on a line parallel with the plane.

4. In an aircraft having a vertically and horizontally streamlined body, a lifting propeller operatively mounted upon an axis adjacent to the center of gravity of the said aircraft, openings arranged in the wings adjacent to the line of the airstream pro-

duced by the said propeller and a means of opening and closing the said openings. 10

In testimony whereof I have signed my name to this specification.

CHARLES S. HALL.

Witness:

DANIEL N. CLARK.
